(57) **CLAIM**

The ornamental design for a filter for water faucet, as shown and described.

DESCRIPTION

FIG. 1 is a top right perspective view showing filter for water faucet, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a side view thereof; and,

FIG. 7 is an opposite side view thereof.

The broken lines shown in the drawings depict portions of the filter for water faucet that form no part of the claimed design.
